WILHELM STIEL, OF BERLIN-SIEMENSSTADT, GERMANY, ASSIGNOR TO WESTINGHOUSE ELECTRIC & MANUFACTURING COMPANY, OF NEW YORK, N. Y., A CORPORATION.

WOOD GRINDER.

Application filed March 31, 1926, Serial No. 98,664, and in Germany March 31, 1925.

My invention relates to wood-grinders with a plurality of grindstones or abrading wheels driven from a common supply of energy. In such grinders as in grinders 5 with a single grindstone or abrading wheel only, the load on the grinding motor is preferably kept approximately constant by correspondingly regulating the pressure with which the wood is forced against the individual 10 grindstones or wheels. For keeping the output of the main driving motor constant, it is in itself sufficient to regulate the total of the pressures at the individual grindstones for constant load. It may, 15 however, happen that the distribution of the load at the individual grindstones or wheels is very different, for instance, if at one grindstone a particularly high friction resistance develops owing to the stone 20 encountering a branch in the wood, while another grindstone encounters cavities contained within the wood fed forward, so that the grindstone is only in contact with portions of the wood and the resistance is very 25 small. The ground wood or pulp will then show an undesirable degree of irregularity.

It has therefore already been proposed to employ for the application pressure at the individual grindstones electric motors of 30 such a characteristic, that their output remains constant irrespective of the application pressure for the time being or the change of speed. Not taking into consideration that such motors are expensive and 35 that for connecting them with the supply of the main motor upon which they must depend, additional apparatus, such as transformers and the like are necessary, the output can really only be kept constant within 40 a relatively narrow range.

In contrast with the known arrangement, I solve the problem by my invention in providing for each feed motor a regulating device which is controlled on the one hand by 45 the load on the main drive and on the other hand by the load of the other feed motors. In this manner it is possible to use as feed motors ordinary regulable motors, the regulation of which requires small currents, so 50 that the plant is not rendered substantially more expensive by the provision of the regulation apparatus.

The control of the regulating apparatus may be effected by the stator as well as by the rotor current of the feed motors. When

making use of the rotor current for the regulation the advantage is attained in comparison with the stator current, that the wattless currents play no part. This arrangement appears therefore according to 60 my invention particularly useful.

In the single figure of the drawing an embodiment of my invention is illustrated 65 diagrammatically by way of example in simplified representation.

The main driving or primary motor 1, which in the illustrated embodiment is contemplated for the drive of two grindstones, is fed from the supply system 2. The feed of the wood in the grinder magazines is effected by the secondary or feed motors 3 and 4, the regulators 5 and 6 of which are operated in known manner by auxiliary motors 7 and 8. These auxiliary motors 7 and 8 are controlled by relays 9 and 10. 70 The relays are controlled on the one hand from the load of the main driving motor and on the other hand from the load of the feed motor appertaining to the other relay. The dependance from the grinding motor may, 75 for instance, be brought about by a tap from a shunt 11 or a transformer in the supply lead of the primary motor. For this purpose the relays 9 and 10 are equipped with coils 19 and 20 which by means of a regulator 12 or the like can be adapted to relatively pre-determined load conditions. Each of the relays 9 and 10 is furthermore provided with an additional coil 29 and 30 80 which in the embodiment illustrated are 85 controlled by the rotor current of the other feed motor 4 or 3. The relays thus represent differential arrangements. When equilibrium prevails, i. e., when the loads are 90 properly distributed, the contact tongue of the relay is located between the regulator contacts 13 and 23 of the auxiliary motors 7 and 8. When the load of one of the feed motors changes, its rotor current also 95 changes and the relay appertaining to the other feed motor responds and controls its feed motor in such a manner that its load is adapted to that of the former motor. The coils 19 and 20 of the relay then take care 100 that the load of the main driving motor is kept constant by the feed motors.

The embodiment illustrated in the drawing is, of course, only an example of carrying out the invention and the invention may 105 be realized by means of other regulator sys- 110

tems of known kind without departing from the principle of my control system. The system may naturally equally well be applied to a different number of grindstones, provided care is taken that each feed motor is able to control the regulating devices of the other motors either directly or indirectly.

The control system according to my invention permits extraordinary extensive fluctuations in the individual magazines and thus ensures the constancy of the load of the main motor within widest limits.

Various modifications and changes may be made without departing from the spirit and scope of the invention, and I desire, therefore, that only such limitations shall be placed thereon as are imposed by the prior art.

I claim as my invention:—

20 1. In an electric feed control system for wood-grinders, a plurality of grindstones adapted to be operated from a common supply of electricity, electric motors for feeding the wood in dependance from the 25 load of the electric main driving motor and a regulating device for each of said feed motors, said devices being adapted to be controlled on the one hand by a load of the main driving motor and on the other hand 30 by the load of the remaining feed motors.

2. In an electric feed control system for wood-grinders, a plurality of grindstones adapted to be operated from a common supply of electricity, electric motors for 35 feeding the wood in dependance from the load of the electric main driving motor, a

regulating device for each of said feed motors, said devices being adapted to be controlled on the one hand by the load of the main driving motor and on the other hand 40 by the load of the remaining feed motors, the rotor current of said motors being employed for the control of said regulating devices.

3. In an electric feed control system for 45 wood-grinders, a main driving motor adapted to be connected with a supply and to drive a plurality of grindstones, motors for feeding the wood forward in the grinder magazines, regulators for said motors, auxiliary motors for operating said regulators and relays for controlling said auxiliary motors, said relays being dependent on the one hand from the load of said main motor and on the other hand from the load of the 50 remaining feed motors.

4. In an electric feed control system for wood-grinders, a main driving motor adapted to be connected with a supply and to 55 drive a plurality of grindstones, motors for feeding the wood forward in the grinder magazines, regulators for said motors, auxiliary motors for operating said regulators, a tap in a shunt in the connecting lead to the said main motor, relays in said shunt, 60 coils in said relays, a regulating member for adapting said coils to relatively predetermined load conditions, and further coils in said relays adapted to be controlled by the rotor current of the remaining feed motors. 65

In testimony whereof I affix my signature.
WILHELM STIEL.
